(57) **CLAIM**

The ornamental design for a fall arrest strap, as shown.

DESCRIPTION

FIG. 1 is a top perspective view of a fall arrest strap showing a first embodiment of my new design;

FIG. 2 is a right side elevation view thereof;

FIG. 3 is a bottom plan view thereof;

FIG. 4 is a left side view thereof;

FIG. 5 is a top plan view thereof;

FIG. 6 is a front view thereof;

FIG. 7 is a rear view thereof;

FIG. 8 is a top perspective view of a fall arrest strap showing a second embodiment of my design;

FIG. 9 is a right side elevation view thereof;

FIG. 10 is a bottom plan view thereof;

FIG. 11 is a left side view thereof;

FIG. 12 is a top plan view thereof;

FIG. 13 is a front view thereof;

FIG. 14 is a rear view thereof; and,

FIG. 15 is a top perspective view of a fall arrest strap showing a third embodiment of my design.

The bottom of the third embodiment is identical to FIG. 3.
